[57] CLAIM

The ornamental design for a thermostat, as shown and described.

DESCRIPTION

FIG. 1 is a perspective view illustrating the front, right side and top of the thermostat;

FIG. 2 is a front elevational view of the thermostat;

FIG. 3 is a bottom plan view of the thermostat;

FIG. 4 is a top plan view of the thermostat;

FIG. 5 is a left side elevational view of the thermostat;

FIG. 6 is a right side elevational view of the thermostat;

FIG. 7 is a back elevational view of the thermostat;

FIG. 8 is a front elevational view of the thermostat when a front cover is rotated about a hinge on the left side to reveal an interior control panel;

FIG. 9 is a top plan view of the thermostat when the front cover is rotated about the hinge to reveal the interior control panel;

FIG. 10 is a bottom plan view of the thermostat when the front cover is rotated about the hinge to reveal the interior control panel;

FIG. 11 is a rear elevational view of the thermostat when the front cover is rotated about the hinge to reveal the interior control panel;

FIG. 12 is a right side elevational view relative to the rear of the thermostat when the front cover is rotated about the hinge to reveal the interior panel; and,

FIG. 13 is a left side elevational view relative to the rear of the thermostat when the front cover is rotated about the hinge to reveal the interior control panel.
